Primary Examiner — Michael A Pratt(74) *Attorney, Agent, or Firm* — Jason A. Houser; Fay Sharpe LLP(57) **CLAIM**

The ornamental design for a gas spring end member, as shown and described.

DESCRIPTION

FIG. 1 is a perspective view of a gas spring end member according to my new design;

FIG. 2 is a top plan view thereof;

FIG. 3 is a bottom plan view thereof;

FIG. 4 is a left side view thereof;

FIG. 5 is a right side view thereof;

FIG. 6 is a rear side view thereof;

FIG. 7 is a front side view thereof; and,

FIG. 8 is a perspective view of the gas spring end member as a part of a gas spring assembly.

The broken lines are for illustrative purposes only and form no part of the claimed design.
